United States Patent Office.

PIETRO CINQUINI, OF MERIDEN, CONNECTICUT, ASSIGNOR TO CHARLES PARKER, OF SAME PLACE.

Design No. 4,874, dated May 9, 1871.

DESIGN FOR COUNTER WEIGHING-SCALES.

The Schedule referred to in these Letters Patent and making part of the same.

To all whom it may concern:

Be it known that I, PIETRO CINQUINI, of Meriden, in the county of New Haven and State of Connecticut, have invented a new Design for Weighing-Scales; and I do hereby declare the following, when taken in connection with the accompanying photographic illustration, to be a full, clear, and exact description of the same, and which said illustrations constitute part of this specification and represent a side view of the scales.

Figure 1, a side view of the scale, complete; and

Figure 2, a perspective view of the base.

This invention relates to a design for the base of weighing-scales or balances, commonly called counter-

scales, and consists in the peculiar design for ornamentation of the base, as fully shown in the accompanying photographic illustrations.

The base or center is of a circular form, with branches extending each way to a smaller base covering the parallel bar.

The ornamentation of the base is fully shown in the accompanying illustrations.

I claim as my invention—

The design for base of weighing-scale, as shown.

PIETRO CINQUINI.
